UNITED STATES PATENT OFFICE

2,576,166

DECORTICATOR

William E. Wright, West Palm Beach, Fla., assignor to Sea Island Mills, Inc., New York, N. Y.

Application May 3, 1947, Serial No. 745,786

11 Claims.

(Cl. 19—11)

1

This invention relates to improvements in fiber decorticating apparatus and particularly to an improved decorticator of the character disclosed in my co-pending application Ser. #677,537 filed June 18, 1946, of which the present application is a continuation in part.

While the decorticator disclosed in my previous application has been tested and operated and has been found to be completely successful in operation, I have found that the operation of that portion which cleans the butt end portions of the fiber bearing plants is materially improved by the provisions of a moveable head cooperating with the butt end cleaning rotor.

It is therefore an object of this invention to provide, in combination with a fiber decorticator as set forth, an improved fiber cleaning mechanism for cleaning the butt ends of plants such as ramie plants the improved mechanism comprising a cleaning rotor at the rear end of the decorticating machine, a head cooperating with the rotor, and mechanism for raising the head away from the rotor and lowering it toward the rotor in timed relationship with the operation with the mechanism of the remainder of the machine with this improvement the butt end portions of the plants may be easily and effectively inserted by the mechanism between the head and the rotor while the head is spaced from the rotor and after the end portions of the plants have been so inserted between the head end and the rotor, the head will be lowered toward the rotor to hold the end portions of the plants firmly against the rotor while the other plant material is removed from the fiber content of these butt end portions of the plants.

Other objects and advantages will be apparent from a consideration of the following description in conjunction with accompanying drawing wherein:

Fig. 1 is a diagrammatic illustration of a decorticating machine of the character referred to in the above mentioned application No. 677,537 showing the application thereto of improved end cleaning mechanism illustrative of the invention;

Fig. 2, an isometric view of the improved mechanism for cleaning the end portions of plants passed through the decorticating machine;

Fig. 3, an isometric view of a fragmentary portion of the mechanism shown in Fig. 2 showing the mechanism in a different operative position from that shown in Fig. 2; and,

Fig. 4, a side elevation on a somewhat enlarged scale of the improved mechanism looking from the side of the machine opposite to that shown in Fig. 1.

2

With continued reference to the drawings, the decorticator comprises a plurality of endless flexible members, such as link chains, arranged in an upper set of one pair of chains and in a lower set of a pair of similar chains. One chain, of the upper set is shown in Fig. 1 and indicated at 10 and a corresponding chain of the lower set is indicated at 11. These chains are supported on sprockets mounted on corresponding shafts 10 journaled in bearings supported by the machine frame in a manner such that each chain is held in a substantially rectangular shape, and adjacent flights of corresponding upper and lower chains are juxtaposed along the entire length of the machine.

Spaced apart transverse clamping bars extend between the two chains of each upper and lower set and are so positioned lengthwise of the chains that a bar carried by the upper chain set is superimposed upon a corresponding bar carried by the lower chain set throughout the juxtaposed intermediate chain flights.

Fiber bearing plants, such as ramie stalks, are fed, butt end first, into the machine through the feed slot 12 and are positioned so that the butt ends contact and are positioned by the pivoted plate 13, the end portions of the plants thus placed in the machine passing between shafts 14 and 15 on which are mounted chain sprockets 30 supporting the chains at the beginning of the intermediate chain flights.

The feed slot is preferably filled with plant stalks having their butt ends resting against the plate 13 and a pair of transverse stalk gripping bars, as indicated at 16 and 17, pass around the chain sprockets carried by the shafts 14 and 15 and are forced together to firmly grip the bundle of stalks near the butt ends thereof. These bars are held together in stalk gripping relationship

40 by suitable chain guides, not illustrated, disposed along the intermediate chain flights, and carry the stalks through the various stages of the decorticating process wherein the plant material is broken up and removed from the fiber contents.

45 As the stalks are dragged past the upper edge of the pivoted plate 13, the leaves and top portions are stripped off. The stalks are then crushed by two sets of crushing rollers, as indicated at 18 and 19. After passing through the crushing rollers the stalks are broken up by a reciprocating beater having an upper portion 20 and a vertically reciprocating blade 21 below the upper portion 20.

50 The stalks are then carried through two scraping devices the first of which has a fluted rotor 22 mounted on a rotatable shaft below the inter-

mediate chain flights and a vertically movable head 23 disposed above the rotor 22. Suitable mechanism is provided to raise the top rollers of the crushing roller sets 18 and 19, the upper portion 20 of the beater mechanism and the head 23 of the first scraper mechanism in timed sequence to permit the pairs of stalk clamping bars to pass through the crushing, beating and scraping devices. A second scraping device includes a fluted rotor 24 mounted above the intermediate chain flights and a movable head 25 positioned below the rotor 24.

Suitable mechanism is provided to lower the head 25 to permit the passage of the pairs of clamping bars between this head and the rotor 24.

The above described fiber cleaning devices are effective to remove all of the other plant material from the fiber content of the portions of the fiber bearing plant stalks which trail the corresponding pair of clamping bars passing through the cleaning devices. The butt end portions of the stalks, held by the clamping bars, are crushed by the bars but are not cleaned by the above indicated cleaning devices.

As the pair of cleaning bars approaches the rear end of the machine, a pair of jaws 26 and 27, disposed one above and one below the intermediate chain flights, come together and grip the cleaned fiber immediately to the rear of the clamping bars. As the bars pass around chain sprockets mounted on the shafts 28 and 29 they separate and release the plane stalks and the stalks are then held by the jaws 26 and 27 with the uncleared butt end portions of the stalks extending from the jaws toward the rear end of the machine. Suitably timed mechanism including the crank shaft 30, crank 31, connecting link 32, cross head 33 and guideways, as indicated at 34 and 35, is provided to impart a longitudinal reciprocating movement to the jaws 26 and 27. The lower jaw is carried by a member 36 fixed to the crosshead 33 while the upper jaw is carried by the member 37 pivotally supported on the crosshead and having a cam arm 38 extending to the opposite side of the pivotal connections from the member 26 and cooperating with the roller 39 to open and close the jaws 26 and 27.

When the jaws 26 and 27 are moved rearwardly of the machine, the butt end portions of the stalks are moved rearwardly until they pass over a fluted cleaning roller 40 mounted on a shaft 41 suitably journaled on the machine frame at the rear end of the machine. A cleaning head 42 cooperates with the fluted rotor 40 to remove other plant material from the fiber contents of the butt end portions of the plant stalks as the stalk end portions are fed between the rotor and the head and withdrawn therefrom by the reciprocating movement of the jaws 26 and 27.

The mechanism so far described is fully disclosed in my copending application Serial #677,537 to which reference may be had for a detailed description of the mechanism.

In the mechanism of the copending application, the head 42 is supported in a substantially fixed position relative to the rotor 40 on suitable brackets carried rearwardly from the machine frame.

In the improved arrangement, however, bracket members 43 and 44 connected to machine frame components 45 and 46 at opposite sides of the machine within the pillow blocks, one of which is indicated at 47, in which shaft 41 is journaled, are apertured for the passage of shaft 41 therethrough and carry apertured lugs or hinge mem-

bers 48 and 49 which extend outwardly from the brackets 43 and 44 respectively at the ends of the rotor 40. Pivoted hinge members 50 and 51 are pivotally connected to the members 48 and 49 respectively by a through shaft 52 which serves as a hinge pin for the hinged construction which supports the cleaning head 42. Head 42 lies between the free end portions of the pivotally mounted hinged members 50 and 51 and has its ends secured to these members.

Standards 53 and 54 extend upwardly from the brackets 43 and 44 respectively and are provided adjacent their upper ends with suitable bearing apertures for a cam shaft 55 having eccentric cams 56 and 57 fixed thereto at locations substantially above the corresponding ends of the cleaning head 42.

A link member 58 has an enlarged end portion surrounding the eccentric circular cam 56 and is pivotally connected at its opposite ends to the head 42 by suitable means, such as the pair of pivot blocks 59 and 60 secured to the top portion of the head 42 and receiving a pivot pin which passes through the blocks and through the lower end of the link 58 to pivotally connect the link to the head. A similar link 61 has an enlarged upper end portion surrounding the eccentric cam 57 and has its lower end portion pivotally connected to the head 42 by the blocks 62 and 63 and the pivot pin 64.

It is apparent that with this arrangement rotation of the shaft 55 and the eccentric cams 56 and 57 will act through the links 58 and 61 to lower the head 42 toward the rotor 40 and raise the head away from the rotor.

A crank arm 65 is secured on one end of the shaft 55 and carries a crank pin 66 upon which is rotatably mounted an end fitting 67 to which the corresponding end of a coiled tension spring 68 is connected. The opposite end of the spring is connected by a suitable hook 69 to a fixed machine frame element 70. A gear 71 is fixed on the opposite end of shaft 55 outside of the standard 54 and is provided with spur teeth which mesh with the teeth of a sector gear 72 mounted on an axle 73 and provided with an upstanding lever 74 the upper end of which is apertured to receive a pivot pin 75 by means of which one end of a link member 76 is connected to the sector gear lever. A slot 77 is provided in the opposite end portion of link 76 and slidably receives a pin 78 secured to an extension 79 extending upwardly from the jaw member 37.

Reciprocating movement of the jaw member 37 will move the pin through the lost motion connection slot 77 and when the pin reaches either end of this slot will move the link 76 to rotate the shaft 55 through the connection provided by the gear 71 and sector gear 72.

A rotatable lever 80 is fixed on the shaft 55 between the crank arm 65 and the standard 53 to provide a convenient means for limiting rotational movement of the cam shaft. This lever 80 has an offset end portion 80' overlying the upper end of the standard 53 and an adjustable stop, in the form of a set screw 81, extends through this offset portion of the lever.

When the lever 80 is in the position illustrated in Fig. 2 the head 42 is raised away from the rotor 40. In this position of the parts the under surface of the offset portion 80' of the lever 80 rests upon an abutment surface 82 provided on the upper end of the standard 53 and effectively limits the rotational movement of the shaft 55 in a clockwise direction as shown in Fig. 2. As

stated above, when the parts are in this relative position the head 42 is raised away from the rotor 40; at the same time, the crank 65 is in a past dead center position relative to the line of force of the spring 68 so that the tension of the spring acts to hold the under surface of the offset portion of lever 80 firmly against the abutment surface 82 of the standard 53.

Assuming now that the members supporting the jaws 26 and 27 are actuated to move the jaws toward the end cleaning rotor 40, during the first part of the travel of these jaws the pin 18 will slide along the slot 77 for the length of the slot. During this part of the movement of the jaws the head 42 will be raised above the rotor 40 and the butt ends of the fiber bearing plants will be fed by the jaws into the space between the end cleaning rotor and corresponding head. The length of the slot 77 is such however that, before the jaws reach the end of their travel toward the end cleaning rotor, the pin 18 will contact the right hand end of slot 77 as viewed in Fig. 1. When this occurs link 76 will be moved to swing the arm 74 of sector gear 72 about its pivotal axis 73 and impart rotation to the spur gear 71. The spur gear 71 is rotated a sufficient amount to move the crank 65 in a counter clockwise direction, as viewed in Fig. 2, to the opposite side of its dead center position relative to the spring 68 from the position shown in Fig. 2. The spring 68 will then contract and rotate the crank 65 together with the cam shaft 55 through a portion of a revolution determined by the lever 80. This spring induced rotation of shaft 55 is such as to move the lever 80 from the position illustrated in Fig. 2 to the position illustrated in Fig. 3 in which the inner end of the adjustable set screw 81 comes in contact with the adjacent side of the standard 53. In the position of the parts shown in Fig. 3, the head 42 will have been lowered to its operative position adjacent to the rotor 40 to press the ends of the plant stalks firmly against the cleaning rotor.

The time of contact of pin **78** with the right hand end of slot **77**, as viewed in Fig. 1, is near the end of the movement of jaw members **26** and **27** toward the end cleaning rotor **40**. As the movement of the jaws is reversed and the ends of the plant stalks are withdrawn from between the rotor **40** and head **42**, the pin **78** will travel back through the length of slot **77** and during this portion of the travel the head will be held in its lowered position adjacent to rotor **40** by the spring **68**. As the jaws approach their limiting position remote from the rotor **40** the pins **78** will contact the left hand end of the slot **77**, as viewed in Fig. 1, and swing the arm **74** to rotate shaft **55** in the opposite direction back to the position illustrated in Fig. 2 in which the head **42** is raised away from the corresponding rotor.

A suitable buffer 83, in the form of a block of rubber, or other suitable resilient material, is secured to the standard 53 in the path of arm 80 so that the arm will strike this buffer in moving to the position illustrated in Fig. 3, just before the end of set screw 81 strikes the side of the standard 53 thereby reducing shock and noise incident to the operation of the device.

Adjustable stops in the form of set screws 84 and 85 extending through the hinged members 59 and 51 respectively are provided to adjustably control the distance between the surface of head 42 adjacent the rotor and the outer surface of rotor 40 when the head is in its lowered position.

The lower ends of these set screws may bear upon suitable abutments provided on the corresponding fixed hinged members 48 and 49, the abutment for the screw 84 being indicated at 86 in Fig. 2.

5 The timed movement of the end cleaning head toward and away from the end cleaning rotor, as provided by the mechanism hereinabove described, greatly facilitates the cleaning of the butt end portions of the fiber bearing plant stalks.

10 and insures that all of such butt end portions will be cleaned whereas with the fixed head arrangement it is possible for some of the plant butt end portions to strike the head and be turned aside from entering the cleaning space between the end cleaning head and rotor. With the improved construction the possibility of the presence of uncleared plant portions in the fiber removed from the machine is substantially eliminated.

15

20 The invention may be embodied in other specific forms without departing from the spirit or essential characteristics thereof. The present embodiment is therefore to be considered in all respects as illustrative and not restrictive, the
25 scope of the invention being indicated by the appended claims rather than by the foregoing description, and all changes which come within the meaning and range of equivalency of the claims are therefore intended to be embraced
30 therein.

What is claimed and desired to be secured by United States Letters Patent is:

1. In a decorticating machine having means operative to grip the butt end portions of the fiber bearing plants and remove other plant material from the fiber content of the portions of said plants extending from said butt end gripping means; means for regripping said plants upon release thereof by said butt end gripping means

35 40 to present the butt end portions of said plants to fiber cleaning means, and a fiber cleaning rotor and a cooperating rotor head positioned to receive the butt end portions of plants presented by said regripping means and remove other plant material from the fiber content of the plant butt end portions; means operative to move said head away from said cleaning rotor to permit the plant butt end portions to enter freely into the space between said head and rotor and to move said head toward said rotor to hold said plant portions against said rotor for cleaning comprising head supporting hinge means having an axis spaced from the axis of said rotor; a shaft rotatably supported above said rotor and having eccentric cams thereon, links pivotally connected to said head operatively connecting said cams with said head, and means operative to rotate said shaft and cams including a crank arm secured to one end of said shaft; a tension spring connected at one end to said crank arm and at the opposite end to a fixed member, stop means connected to said cam shaft to hold said shaft in one operative position with said head raised from said rotor and said crank arm in a past dead center condition relative to said spring, a bar having a lost motion connection with said

45 50 55 60 65

70 having a lost motion connection with said regripping means and a gear and sector connection with said cam shaft operative upon movement of said regripping means to move said plant end portions into the space between said head and said rotor to rotate said crank arm over its dead center position to enable said spring to rotate said cam shaft in a direction to lower said head toward said rotor, and an adjustable stop for said

cam shaft whereby lowering movement of said head may be limited.

2. In a decorticating machine having means operative to clamp the butt end portions of fiber bearing plant stalks fed into one end of the machine and carry said plant stalks to the opposite end of the machine, cleaning means operatively disposed between the ends of said machine to remove all other plant material from the fiber content of the plant stalk portions extending from the clamping means, machine carried reciprocatory means operative to grip cleaned fiber portions of said plant stalks when the stalk butt end portions are released by said clamping means, and an end cleaning rotor and head at said opposite end of said machine in position to receive and clean butt end portions of plant stalks presented thereto by said reciprocatory gripping means; means operatively connected between said gripping means and said head maintaining said head raised away from said rotor while plant stalk butt end portions are fed between said head and rotor and lowering said head toward said rotor to clean said plant end portions.

3. In a fiber decorticating machine having means operative to clamp the butt end portions of fiber bearing plant stalks and carry said stalks in continuously clamped condition past fiber cleaning devices, an end cleaning device comprising a cleaning rotor and associated head for cleaning the butt end portions of the plant stalks; and reciprocating jaw means operative to grip the plant stalk portions when released by said clamping means and present the butt end portions of said stalks to said end cleaning device; means for moving said end cleaning rotor head toward and away from said end cleaning rotor in timed relationship to the reciprocatory movement of said jaw means comprising a pair of fixed brackets disposed one at each side of said machine opposite the ends of said head; hinge means supporting said head for movement toward and away from said associated rotor; cam means supported by said brackets adjacent said head; means operatively connecting said cam means with said head; spring means operative to turn said cam means between two limiting operative positions in one of which said head is raised away from said rotor and in the other of which said head is disposed in fiber cleaning position adjacent said rotor; and a lost motion connection between said cam means and said jaw means operative to control the cam turning operation of said spring means in accordance with the reciprocatory movements of said jaw means.

4. In a fiber decorticating machine having means operative to clamp the butt end portions of fiber bearing plant stalks and carry said stalks in continuously clamped condition past fiber cleaning devices, an end cleaning device comprising a cleaning rotor and associated head for cleaning the butt end portions of the plant stalks; and reciprocating jaw means operative to grip the plant stalk portions when released by said clamping means and present the butt end portions of said stalks to said end cleaning device; means for moving said end cleaning rotor head toward and away from said end cleaning rotor in timed relationship to the reciprocatory movement of said jaw means comprising a pair of fixed brackets disposed one at each side of said machine opposite the ends of said head; means guiding said head for movements toward and away from said rotor; head moving means

carried by said brackets adjacent said head, resilient means operatively connected with said head moving means actuating said head moving means to quickly move said head toward and away from said rotor; and a lost motion connection between said head moving means and said jaw means operative to initiate actuation of said head moving means in accordance with the reciprocatory movements of said jaw means.

5. In a fiber decorticating machine having means operative to clamp the butt end portions of fiber bearing plant stalks and carry said stalks in continuously clamped condition past fiber cleaning devices, an end cleaning device comprising a cleaning rotor and associated head for cleaning the butt end portions of the plant stalks; and reciprocating jaw means operative to grip the plant stalk portions when released by said clamping means and present the butt end portions of said stalks to said end cleaning device; means for moving said end cleaning rotor head toward and away from said end cleaning rotor in timed relationship to the reciprocatory movement of said jaw means comprising a pair of fixed brackets disposed one at each side of said machine opposite the ends of said head; means guiding said head for movement toward and away from said rotor; head moving means carried by said brackets adjacent said head comprising a shaft journalled in said brackets, eccentric cams on said shaft between said brackets, pivoted links connecting said cams with said head, a crank arm on one end of said shaft and a gear on the opposite end thereof; spring means operatively connected with said crank arm to rotate said shaft and said cams to thereby move said head toward and away from said rotor; and means operatively connecting said jaw means to said shaft through said gear to initiate rotation of said shaft in timed relationship to reciprocatory movements of said jaw means.

6. In a fiber decorticating machine having means operative to clamp the butt end portions of fiber bearing plant stalks and carry said stalks in continuously clamped condition past fiber cleaning devices, an end cleaning device comprising a cleaning rotor and associated head for cleaning the butt end portions of the plant stalks; and reciprocating jaw means operative to grip the plant stalk portions when released by said clamping means and present the butt end portions of said stalks to said end cleaning device; means for moving said end cleaning rotor head toward and away from said end cleaning rotor in timed relationship to the reciprocatory movement of said jaw means comprising a pair of fixed brackets disposed, one at each side of said machine opposite the ends of said head; means guiding said head for movements toward and away from said rotor, head moving means including a cam shaft carried by said brackets adjacent said rotor; spring means operatively connected to said cam shaft to impart head moving rotational movements thereto; and means operatively connecting said jaw means and said cam shaft to initiate rotational movements of said cam shaft in timed relationship to the reciprocatory movements of said jaw means comprising a gear on said cam shaft, a second gear pivoted on the bracket at the corresponding end of the cam shaft and meshing with said cam shaft gear; a lever arm secured to said second gear; a link pivotally connected at one end to said lever arm and provided in its

opposite end portion with an elongated slot; and a pin fixed to said jaw means and slideable in said slot, said slot being of a length such that said pin imparts gear turning movement to said link at each end of the reciprocatory movement of said jaw means.

7. Decorticating apparatus for cleaning the fiber content of fiber bearing plant stalks comprising cleaning means operative to clean the fiber except for the butt end portions of the stalks and means operative to clean the fiber in the butt end portions; feed means for feeding said butt end portions into said end cleaning means; and means operative by said feed means and in timed relation thereto to adjust said end cleaning means for the reception of butt end portions fed thereto by said feed means.

8. Decorticating apparatus comprising means for holding fiber bearing plant stalks; fiber cleaning means movable relative to said holding means; means comprising a rotor and corresponding head disposed at the rear of the apparatus and constructed to clean the fiber content in the butt end portions of the stalks; a second holding means for holding said stalks during cleaning of the butt end portions, said second holding means being movable relative to said rotor and head to feed said butt end portions thereto and means operative to produce relative movement between said head and said rotor in timed relationship to the relative movement of said second holding means to facilitate feeding of the butt end portions of the stalks between said rotor and head.

9. Decorticating apparatus comprising means for holding fiber bearing plant stalks; fiber cleaning means movable relative to said holding means to clean the fiber content of plant stalks; means comprising a rotor and corresponding head at the rear of the apparatus to clean the fiber content of the butt end portions of the stalks; resilient means operative to produce relative movement between said head and said rotor to facilitate feeding of the butt end portions of plant stalks therebetween; and means operated by relative movement of said holding means and

cleaning means for said butt end portions to control the action of said resilient means in timed relationship to the relative movement of said holding means and cleaning means for said butt end portions.

10. Decorticating apparatus for cleaning the fiber content of fiber bearing plant stalks comprising cleaning means operative to clean the stalks except for the butt end portions thereof; end cleaning means including a rotor and head arranged to clean the butt end portions; and means operatively connected with said end cleaning means to separate said rotor and head for the admission of stalk butt end portions therebetween, and to close said rotor and head for cleaning the butt end portions of the stalks.

11. In decorticating apparatus for cleaning the fiber content of fiber bearing plant stalks and comprising fiber cleaning means operative to clean the fiber content of the stalks except for the butt end portions thereof, end cleaning means for cleaning the fiber content of the butt end portions of the stalks after the other portions thereof have been cleaned, and reciprocating feed means operative to feed the plant butt end portions into said end cleaning means and withdraw them therefrom; means operative by said feed means and in timed relation thereto to adjust said end cleaning means for the reception of plant stalk butt end portions comprising cam means operatively connected with said end cleaning means, resilient means operatively connected with said cam means, and timing means operatively connected between said reciprocating feed means and said cam means.
